UNITED STATES PATENT OFFICE

ARTHUR S. ALLEN, OF NEW YORK, N. Y., ASSIGNOR TO PAC-KUPS INCORPORATED, OF EASTON, PENNSYLVANIA, A CORPORATION OF PENNSYLVANIA

DESIGN FOR A PAPER CUP OR SIMILAR ARTICLE

Application filed March 18, 1930. Serial No. 34,957. Term of patent 14 years.

To all whom it may concern:

Be it known that I, ARTHUR S. ALLEN, a citizen of the United States, residing at New York, in the county of New York and State of New York, have invented a new, original, and ornamental Design for Paper Cups or Similar Articles, of which the following is a specification, reference being had to the accompanying drawing, forming part thereof.

In the drawings:—

Figs. 1 and 2 are side elevations at different points in the circumference of the cup showing my new design.

I claim:

The ornamental design for a paper cup or similar article as shown.

ARTHUR S. ALLEN.
